Carl L. Otto, New York, N. Y., assignor to The
Torsion Balance Company, Clifton, N. J., a cor-
poration of New York

Application February 7, 1952, Serial No. 18,425

Term of patent 14 years

(Cl. D52—10)

To all whom it may concern:

Be it known that I, Carl L. Otto, a citizen of the United States of America, residing in the Borough of Manhattan, city, county, and State of New York, have invented a new, original, and ornamental Design for a Laboratory Scale, of which the following is a specification, reference being had to the accompanying drawings, forming part thereof, wherein:

Figure 1 is a front elevational view of a laboratory scale showing my new design.

Fig. 2 is a top plan view of Fig. 1.

Fig. 3 is a side elevation as viewed from the left hand side of Fig. 1.

Fig. 4 is a rear elevational view of Fig. 1.

Fig. 5 is a side elevation as viewed from the right hand side of Fig. 1.

I claim:

The ornamental design for a laboratory scale, as shown.

CARL L. OTTO.
